The ornamental design for pediatric dental x-ray film holder, substantially as shown and described.

DESCRIPTION

FIG. 1 is a perspective view showing the front and left side of a pediatric dental x-ray film holder, showing my new design;

FIG. 2 is a perspective view showing the front and right side thereof;

FIG. 3 is a top plan view thereof;

FIG. 4 is a rear elevational view thereof;

FIG. 5 is a bottom plan view thereof;

FIG. 6 is a front elevational view thereof;

FIG. 7 is a left side elevational view thereof; and,

FIG. 8 is a right side elevational view thereof.

The broken line showing is for illustrative purposes only and forms no part of the claimed design.
